(57) CLAIM

The ornamental design for a combined flashlight and power bank, as shown and described.

DESCRIPTION

FIG. 1 is a perspective view of the combined flashlight and power bank showing my new design;

FIG. 2 is a second perspective view of the combined flashlight and power bank;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken line showing represents unclaimed portions of the article and forms no part of the claimed design.
